(57) **CLAIM**

The ornamental design for a food container, as shown and described.

DESCRIPTION

FIG. 1 is a top perspective view of a food container, showing my new design;

FIG. 2 is bottom perspective view thereof;

FIG. 3 is a front elevation view thereof, the rear elevation view is identical;

FIG. 4 is a left side elevation view thereof, the right side elevation view is identical;

FIG. 5 is a top plan view thereof;

FIG. 6 is a bottom plan view thereof;

FIG. 7 is an enlarged view of a portion of the food container shown within the area designated as 7 in FIG. 1;

FIG. 8 is an enlarged view of a portion of the food container shown within the area designated as 8 in FIG. 1;

FIG. 9 is an enlarged view of a portion of the food container shown within the area designated as 9 in FIG. 2; and,

FIG. 10 is an enlarged view of a portion of the food container shown within the area designated as 10 in FIG. 2. The broken lines in FIG. 2 and FIG. 6 are for the purposes of illustrating portions of the food container, that form no part of the claimed design. The broken lines encircling portions of the food container in FIGS. 1 and 2 and illustrated in enlarged views in FIGS. 7-10 form no part of the claimed design.

1 Claim, 8 Drawing Sheets
